COLLAPSIBLE BOX

Filed March 20, 1929

FIG. 2.

THE END

FIG. 4

INVENTOR:
Louis J. Spitzenberger
BY David E. Larsen
ATTORNEY.

UNITED STATES PATENT OFFICE

LOUIS J. SPITZENBERGER, OF ST. PAUL, MINNESOTA

COLLAPSIBLE BOX

Application filed March 20, 1929. Serial No. 348,489.

My invention relates to boxes in general and more particularly to boxes made of paper, cardboard, fibre and other suitable flat material and to be used for various purposes such as containers for candy, pills, or like articles. The main object is to provide a substantial box made of a single piece of material and adapted to be easily and readily assembled for use, without the necessity of using glue or like holding means. This box is the so-called shoulder type most commonly used as in drug stores for holding a quantity of pills, powders and the like. In larger sizes it is practical for candy, stationery, cards and other merchandise. Further objects and advantages of my improved box are hereinafter fully set forth reference being had to the accompanying drawing in which,

20 Fig. 1 is a plan view of a blank sheet or form showing a blank for a square type shallow box.

Fig. 2 is a top view of a box assembled from a blank of the type illustrated in Fig. 1, the 25 top or cap part of the box being shown in opened position.

Fig. 3 is a rear edge view of the box shown in Fig. 2 and closed.

Fig. 4 is a perspective view of my improved 30 box with the cover raised, the nearside flange of said cover broken to give a clear view of the interior.

Fig. 5 is a top view of the box shown in Fig. 2, looking down on the cap, the box being 35 closed.

Referring to the drawing by reference numerals, I have illustrated a blank form adapted to be assembled to provide a square type shallow box of the so-called shoulder type best shown in Fig. 4, but it will be readily understood that its features of details, proportions and assembling may be varied to provide finished boxes of other shapes, a 40 square type being shown and described to best advantage.

In Fig. 1 heavy black outlines indicate the 45 outline and cuts of the blank from which a box as shown in Figs. 2, 3, 4 and 5 is assembled. Dotted lines indicate creases or folding

lines in the blank to facilitate the assembling or forming of the box.

5 is a top panel, 6 a like base or bottom panel, and 7 is a false-bottom panel arranged to lie on panel 6 when the box is assembled. 55 Panels 5 and 6 are separated normally by an integral strip 5H having a central crease 5H' serving as a hinge for the assembled cover of the box and the width of said strip determining the depth of the box. 5F and 5G 60 are right and left side flanges formed integral with panel 5 and divided therefrom only by crease lines 11, while 5C is a like flange adjoining at line 12 the outer edge of panel 5. To the right and left of said flange 5C are adjoining flange sections 5D and 5E (right) and 5A and 5B (left) of which 5E and 5A 65 are at the extreme right and left, flange 5A having an upwardly opening central notch 13 and flange 5E having a like downwardly 70 opening notch 14. Likewise the bottom panel 6 has an adjoining outer flange 6C, left side flange 6F and right side flange 6G. To the right of flange 6C are two alined flanges 6D and 6E, and to the left thereof like flanges 75 6B and 6A. The outermost of said latter flanges 6A and 6E have notches 13A and 14A corresponding to notches 13 and 14 previously described and for a purpose to be pres- 80 ently stated.

7A, 7B, 7C, 7D and 7E is a row of flanges adjoining each other on the creases 15 and panel 7A connected at crease 16 to the strip 5H separating the top and bottom panels 5 and 6. The false bottom 7 adjoins panel 7D 85 on crease line 17 and 7E is a comparatively short flange at the extremity of the line of flanges 7A-7E inclusive. These wide flanges (7A-7E incl.) are approximately the same width as the strip 5H and extend preferably 90 one way therefrom in parallel relation to the respective upper and lower lines of flanges 5A to 5E and 6A to 6E.

The assembling of the box from its blank 95 form is a simple process. Assuming that an operator is about to assemble a box from a blank as illustrated in Fig. 1, he first bends the wide flanges 7A-7E inclusive at their creases 15-16 into square formation with the short piece 7E bearing against the inner 100

end part of flange piece 7A (see Fig. 2). Then the false bottom 7 is bent on line 17 to lie in a plane common to the bottom edges of the flanges 7A-7E inclusive. This quadrangular formation is then arranged to stand upright on the bottom 6 and concentric thereto of the false bottom 7 resting or lying concentric on said base 6. Then the side panels 6F and 6G are folded upwardly against the respective upright side pieces 7A and 7C. Then flange 6C of the base is bent up on its crease 18 to bear against the outer lower part of section 7B (Fig. 2) and the respective right and left continuation flanges 6D and 6B are folded in against the sections 6G and 6F of the base 6. Thus the extreme end parts 6E and 6A protrude rearwardly from the strip 5H which is now of course in vertical plane, and said pieces 6E and 6A are folded toward each other against the back of strip 5H and interlocked at their notched parts 13A and 14A (see Fig. 3).

It will now be understood that a double walled upwardly opening box body (as Fig. 4) has been assembled, in which the inner and wider quadrangularly formed panels 7A to 7E inclusive project upwardly from the false bottom 7, and project above the upper edge of the similarly formed exterior flanges 6A, 6B, 6C, 6D and 6E, bearing inwardly on the exterior faces of the wider flanges, thus forming the shoulder effect as at S in Fig. 4.

Now the cover is similarly formed by first folding its side panels 5F and 5G up at right angles from the cover panel 5, then folding the outer multi-section flange (5A-5E inclusive) upwardly so that section 5C closes the third side of panel 5, forming a U-shape in connection with the flange pieces 5F and 5G. Then the sections 5D and 5B are folded inwardly against the outer faces of side panel flanges 5G and 5F respectively. Thus the top panel is inclosed on three sides by said flanges 5F, 5G, 5B, 5C and 5D and the fourth side comprises the upper half of strip 5H (above crease 5H'). Said fourth side is further reinforced and the cover made rigid and held assembled by folding the extreme flanges 5A and 5E toward each other against the upper half of strip 5H and interlocking them at the notches 13-14 (see Fig. 3). Now the cover is complete and integrally connected to the main box at the crease 5H' of the strip 5H which latter is in reality the outer rear wall of the box proper.

The cover of course can be swung forward and down to fit snugly about the quadrangularly arranged protruding parts of the flanges 7A-7E inclusive and stops against the shoulder S. The box thus closed (as in Figs. 3 and 5) is substantial and well set up, resists breaking and is practical in various sizes for different purposes.

Hitherto, in the box industry, small paper

boxes particularly have been assembled and shipped ready for use, obviously taking up much space. Such boxes, as now made, are also assembled in a costly manner involving use of glue. My improved box may be shipped in blank form in a minimum of space and is readily assembled at shipping destination or assembled only one at a time as needed.

I claim:

1. A box made of a single integral piece of flat material and including a base panel, a false bottom adapted to lie concentric on said base panel, a cover panel and an integral spacing strip between said base and top panels, a multi-section wide flange strip extending from one end of said spacing strip and one of said sections adjoining a side of said false bottom panel, a like but narrower flange strip adjoining the outer edges of the top and bottom panels and a side extension strip extending outwardly from each side of the top and bottom flanges, crease lines at all said adjoining parts, said wide flange strip arranged to be bent into square formation and upright around the four sides of the false-bottom panel when the latter is laid upon the base panel, said narrow flange strip at the outer side of the base panel arranged to be bent up and thence about and against the outer sides of said wide flanges and the extreme outer sections of said narrow flange arranged to overlap at the rear side of the box and interlocked to bear against the lower half of the spacing strip raised upright from the base panel.

2. The structure specified in claim 1 and said cover consisting of two side flanges formed integral of the cover panel and bent up at right angles to the panel, and its said multi-section flange strip arranged to be bent up also in upright plane and its sections arranged in square formation with two flange sections bearing against the outer sides of said panel side sections and the extreme end sections of said flange arranged to be overlapped and interlocked against the outside and upper half of said spacing strip.

3. A box made of a single piece of flat material comprising a base panel, a top or cover panel and a false-bottom panel, a spacing strip between said cover and base panels, multi-section flange strips formed integral with each said cover and base panel, and single section side flanges formed integral with said cover and base panels, all said sectional parts separated by crease lines or an equivalent to readily bend the flange strips in continuous formation about their respective panels and upright thereon, each box body comprising the false bottom panel and its flange members about it and lying concentric on the base panel and subsequently raising the flange parts of said base and against the flange parts of the false bottom and means for interlocking the said base

flanges to inclose the lower areas of the false base-panel flanges.

4. The structure specified in claim 3 and each box cover comprising said cover panel, its side flanges raised upright thereon and its multi-section flange also raised and bent at the crease lines to form a quadrangular upright flange about the cover panel and its raised side flanges and means for interlocking the end sections of said multi-section flange at one side of the said cover panel, said cover assembled forming a shallow member with perimetrical flange and adapted to be pressed down upon the upwardly directed perimetrical flange formed by the adjacent upwardly directed flange sections of the false-bottom panel, substantially as shown and described.

In testimony whereof I affix my signature.

LOUIS J. SPITZENBERGER.
